UNITED STATES PATENT OFFICE.

GEORGE J. SCHNEIDER, OF DETROIT, MICHIGAN, ASSIGNOR TO ACME ELECTRIC
HEATER COMPANY, OF DETROIT, MICHIGAN, A CORPORATION OF MICHIGAN.

ATTACHMENT-CONDUCTOR FOR ELECTRICAL INSTRUMENTS.

1,118,953.

Specification of Letters Patent.

Patented Dec. 1, 1914.

Application filed January 16, 1911. Serial No. 602,879.

To all whom it may concern:

Be it known that I, GEORGE J. SCHNEIDER, a citizen of the United States of America, residing at Detroit, in the county of Wayne 5 and State of Michigan, have invented certain new and useful Improvements in Attachment-Conductors for Electrical Instruments, of which the following is a specification, reference being had therein to the 10 accompanying drawings.

The invention relates to attachment conductors for electrical instruments and consists in the novel construction of means for protecting, and preventing twisting or 15 kinking of the flexible conductor, and further in the construction of the attachment plug as more fully hereinafter set forth.

In the drawings, Figure 1 is an elevation of the attachment conductor shown as used in connection with an electrically heated sad-iron; Fig. 2 is a sectional elevation of the plug; Fig. 3 is a similar view of the plug for the opposite end of the 25 conductor; Fig. 4 is a perspective view of several parts composing the plug, detached.

It is usual in the construction of attachment conductors to provide a flexible cord having the conductors in separate strands 30 braided or twisted together. Such constructions provide flexibility but in use it frequently occurs that the conductor becomes twisted or tangled so as to interfere with the freedom of movement of the instrument. 35 This is particularly true in the case of electrically heated sad-irons.

It is one of the objects of the present invention to avoid this difficulty by providing means for resisting the twisting of 40 the conductor, and also for automatically straightening the conductor when released, the construction being as follows:

A is an attachment plug suitable for connection with any standard construction of 45 fixture, B is the flexible attachment conductor leading from this plug to the instrument such as the sad-iron C, and D is the attachment plug at the opposite end of said conductor for engagement with the instrument. 50 The body of the attachment conductor B is formed in any suitable manner as by twisted strands E of insulated flexible conducting wire. Surrounding this is a metallic coil

or helix F which forms both the armor for protecting the insulated conductors and also 55 by its resiliency resists the kinking or twisting of the cord. This helix extends the entire length of the cord and at its opposite ends is attached to the plugs A and D, the connection between each end of the cord and 60 its respective plug preventing relative rotary movement between the cord end and the plug. A

The attachment plug D is preferably of the construction shown in detail in Figs. 2 65 and 4 comprising an armor, and insulated contact terminals insertible into a socket in the electrical instrument. The contact terminals G and G' are formed of pairs of resilient metallic strips electrically connected 70 with the conductor strands E located in longitudinally extending recesses H in the body I of porcelain or other insulating material. Adjacent to this porcelain insulator are insulator blocks J 75 preferably formed of hard asbestos or other insulator less brittle than the porcelain, said blocks J being clamped on opposite sides of the conductor and being secured to the porcelain insulator for a metallic sheath 80 K and screws L. When the parts are assembled the contacts G, G' are located on opposite sides of the central division wall H' of the insulator H, while the opposite edges of said insulator are cut-away or 85 slotted at H' to permit of engagement with the coöperating contact members M, M'. These coöperating members are arranged in alinement with each other but are separated by an air gap for insulation, and as sufficient 90 width to permit the insertion of the division wall H' therebetween.

For attaching the helix F to the plug D the blocks J are provided with annular grooves P which engage an enlarged coil at 95 the end of the helix and prevent it from being withdrawn. Thus in use whenever the instrument is turned or twisted it will place the helix F under tension and the instant that the cord is released the reaction of the 100 helix will again straighten it. If therefore, the cord becomes twisted by the turning of the instrument it is only necessary to pull out the attachment plug D and the helix will then cause the automatic untwisting. 105 The helix F is also useful as an armor

in protecting the insulation of the cord from abrasion or other injury.

What I claim as my invention is:

An attachment conductor for electrical instruments comprising a flexible insulated conductor, contacting plugs at opposite ends of said conductor non-rotatively attached thereto, and a resilient helix surrounding said conductor extending continuously from

plug to plug and non-rotatively attached to 10 said plugs.

In testimony whereof I affix my signature in presence of two witnesses.

GEORGE J. SCHNEIDER.
